UNITED STATES PATENT OFFICE

EDWIN A. BESCHERER, OF BROOKLYN, AND ARTHUR ZITZMANN, OF OZONE PARK, NEW YORK, ASSIGNORS TO BELL TELEPHONE LABORATORIES, INCORPORATED, OF NEW YORK, N. Y., A CORPORATION OF NEW YORK

DESIGN FOR A COMBINED TABLE AND COVER FOR TELEGRAPH PRINTER

Application filed June 20, 1931. Serial No. 40,288. Term of patent 14 years.

To all whom it may concern:

Be it known that we, EDWIN A. BESCHERER and ARTHUR ZITZMANN, citizens of the United States, residing at Brooklyn, in the county of Kings and State of New York, and at Ozone Park, in the county of Queens and State of New York, respectively, have invented a new, original, and ornamental Design for Combined Table and Cover for Telegraph Printer, of which the following is a specification, reference being had to the accompanying drawing, forming part thereof.

Fig. 1 of the drawing is a perspective view

of the printer table with the cover in place showing our new design;

Fig. 2 is a plan view of the printer cover alone; and

Fig. 3 is a side view of the combined printer table and cover.

We claim:

The ornamental design for a combined table and cover for telegraph printer as shown.

In witness whereof, we hereunto subscribe our names this 15th day of June, 1931.

EDWIN A. BESCHERER.
ARTHUR ZITZMANN.
